181,840

ROOM DEODORIZER OR THE LIKE

Aurelio Dello Russo, Bronx, N. Y., assignor to Airkem, Inc., New York, N. Y., a corporation of New York

Application January 10, 1957, Serial No. 44,471

Term of patent 14 years

(Cl. D16—2)

Fig. 1.

Fig. 2.

Fig. 3.

Fig. 1 is a side elevation view of a room deodorizer or the like embodying my design and showing the inner and outer telescoping parts thereof in the contracted or closed position;

Fig. 2 is a sectional view taken on the line 2—2 of Fig. 1 looking in the direction of the arrows; and

Fig. 3 is a fragmentary detail view of the telescoping top shown in Fig. 1 with portions broken away for convenience of illustration.

I claim:
The ornamental design for a room deodorizer or the like, as shown.
